CLAIM

The ornamental design for a display screen or portion thereof with graphical user interface as shown and described.

DESCRIPTION

The patent or application file contains at least one drawing executed in color. Copies of this patent or patent application publication with color drawing(s) will be provided by the Office upon request and payment of the necessary fee. The FIGURE is a front view of a display screen or portion thereof with graphical user interface showing the claimed design.

The broken lines in the Figure show a display screen or portion thereof, and form no part of the claimed design. Elements shown in solid lines form the claimed design. The rounded corner square and the circular element with an "x" bounded by solid lines form the claimed design. The areas within the rounded corner square and between the rounded corner square and the outer broken lines shown in a reduced opacity form no part of the claimed design.
